Primary Examiner — Ryan Harvey(74) *Attorney, Agent, or Firm* — Schmeiser, Olsen & Watts, LLP(57) **CLAIM**

The ornamental design for a pillared exerciser, as shown and described.

DESCRIPTION

FIG. 1 is a top perspective view of the pillared exerciser, showing my new design.

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and;

FIG. 7 is a bottom plan view thereof; and,

FIG. 8 is a top perspective view thereof, showing an unclaimed pattern thereon.

The broken line showing of a surface pattern in FIG. 8 depicts environment and forms no part of the claim.

1 Claim, 4 Drawing Sheets(56)
